UNITED STATES PATENT OFFICE.

ALEXANDER H. KOPETSCHNY, OF JERSEY CITY, NEW JERSEY.

DESIGN FOR A BADGE.

No. 38,500.

Specification for Design.

Patented April 2, 1907.

Application filed March 4, 1907. Serial No. 360,622. Term of patent 14 years.

To all whom it may concern:

Be it known that I, ALEXANDER H. KOPE TSCHNY, a citizen of the United States, and a resident of Jersey City, in the county of Hudson and State of New Jersey, have invented a new, original, and ornamental Design for a Badge, of which the following is a specification, reference being had to the accompanying drawing, forming part thereof.

The figure is a perspective view of a badge, showing my new design.

I claim—

The ornamental design for a badge, as shown.

ALEXANDER H. KOPETSCHNY.
